UNITED STATES PATENT OFFICE.

JOHN MONCRIEFF, OF NEW YORK, N. Y.

WINDOW-CLEANING DEVICE.

Application filed December 20, 1923. Serial No. 681,867.

To all whom it may concern:

Be it known that I, JOHN MONCRIEFF, a citizen of the United States, residing at New York, in the county of New York and 5 State of New York, have invented certain new and useful Improvements in Window-Cleaning Devices; and I do declare the following to be a full, clear, and exact description of the invention, such as will enable 10 others skilled in the art to which it app pertains to make and use the same.

My invention relates to improvements in window cleaning devices and its principal object is to provide a simple and inexpensive, yet an efficient and desirable arrangement of parts, whereby both the outer and the inner sides of a window pane may be simultaneously cleaned while the operator of the device stands within the building.

With the foregoing in view, the invention resides in the novel subject matter hereinafter described and claimed, the description being supplemented by the accompanying drawing.

Figure 1 is a side elevation showing one form of the invention applied to a window sash.

Figures 2 and 3 are vertical sectional views as indicated by lines 2-2 and 3-3 30 of Fig. 1.

Figure 4 is a perspective view of one of the cleaning elements.

Figure 5 is a fragmentary perspective view of a portion of the construction shown 35 in the preceding figures.

Figure 6 is a detail sectional view of the upper belt roller.

Figure 7 is a view similar to Fig. 5, but illustrating a different form of construction.

Figure 8 is a vertical sectional view, similar to Fig. 2, but showing the construction illustrated in Fig. 7.

Figure 9 is a plan view of the upper 45 rollers of Figs. 7 and 8.

In the drawings above briefly described, the numerals 1 designate an upper pair of clamps adapted to straddle the upper rail of a window sash, while the numerals 2 50 designate similar clamps to straddle the lower rail of the sash. Each of the clamps 1 and 2 is preferably of the U-shaped construction shown and its arm portions 3 are preferably pivoted together as indicated at 55 4, to permit them to be moved inwardly and outwardly, and means such as the screw 5

and any desired spring such as 5' are provided for drawing said arms into clamping relation with the sash rail. In the form of construction shown, the free ends of the 60 arms 3 are flattened as indicated at 6, and said ends of the upper clamps as well as the corresponding ends of the lower clamps, are connected by horizontal rods 7 for disposition at opposite sides of the window 65 pane, to hold certain belting, hereinafter described, in close relation with said pane. At suitable locations, other horizontal rods 8 may extend between the clamps to hold the belting against dragging upon the upper and lower sash rails.

In the construction shown in Figs. 1 to 5, a rod 9 extends horizontally between the upper clamps 1 and another such rod extends between the lower clamps 2, and 75 flanged rollers 9^a are rotatable and slidable on these rods. A suitable belt 10 is trained around the rollers 9^a and properly engaged with the rods 7 and 8, so that the two reaches of said belt may be disposed at 80 opposite sides of the window pane. This belt is provided with a suitable buckle or the like 11, which permits it to be passed around the window sash and also allows for adjustment. Suitable cleaning elements 85 12 are connected with the inner and outer reaches of the belt 10, by appropriate spring clips or the like 13, each of said cleaning elements being preferably formed of a back 14, a pad 15 engageable with said back and 90 having its ends turned around the ends thereof, and a pair of pivoted yokes 16 carried by the back for engaging the turned ends of the pad and securing the latter to the back, this construction being most clearly illustrated in Fig. 4.

It will be seen that after properly applying the device to the window sash, the inner reach of the belt 10 may be gripped by hand and moved upwardly and downwardly, as well as laterally, thus simultaneously causing both of the cleaning elements 12 to move over the surface of the window pane. During the cleaning operation, the rollers 9^a rotate and slide on the rods 9, 105 according to the manner in which the belt is moved.

In the construction shown in Figs. 7, 8 and 9, two rollers 9^b are used at top and bottom, mounted on rods 9^c and geared together 110 at 17. Two belts 10^a carrying cleaning elements 12^a are engaged with the upper and

lower rollers. Links 18 connect the hubs 19 of the rollers 9^b so that these rollers must move together along the rods 9^a.

In operating the form of construction just described, the inner belt 10^a is operated merely by moving it upwardly and downwardly and at the same time exerting lateral pressure thereon in one direction or the other, and the outer belt will be similarly moved, due to the links 18 and gears 17.

While I have illustrated the preferred forms of my invention, it is to be understood that numerous changes may be made within the scope of said invention as claimed.

I claim:

1. A window cleaner comprising a pair of upper U-shaped clamps adapted to straddle the upper rail of a sash, a pair of lower U-shaped clamps adapted to straddle the lower rail of the same sash, upper and lower horizontally elongated belt guiding means extending between the upper clamps and between the lower clamps, cleaner-carrying belting trained around said means and having reaches for disposition at opposite sides of the sash, and horizontal rods extending between the sash-straddling arms of said clamps for holding the cleaner-carrying reaches of the belting in close relation with the pane of the sash.

2. A structure as specified in claim 1, together with additional horizontal rods extending between the arms of said clamps to prevent the belting from dragging upon the upper and lower rails of the sash.

3. A window cleaner comprising upper and lower clamps adapted to grip the upper

and lower rails of a window sash respectively, each of said clamps being formed of two relatively movable rail-gripping sections and means for moving said sections inwardly toward each other, horizontally elongated belt-guiding means carried by said clamps to extend along the edges of the sash, and cleaner-carrying belting trained around said belt-guiding means and having reaches for disposition at opposite sides of the sash.

4. A window cleaner comprising upper and lower clamps adapted to grip the upper and lower rails of a window sash respectively, upper and lower guide rods carried by said clamps and adapted to extend along the edges of the sash, flanged belt-guiding rollers rotatable and slidable along said rods, and cleaner-carrying belting trained around said rollers and having reaches for disposition at opposite sides of the sash.

5. A window cleaner comprising upper and lower clamps adapted to grip the upper and lower rails of a window sash respectively, upper and lower pairs of rods carried by said clamps, flanged belt rollers rotatable and slidable along said rods, links connecting the rollers of each pair of rollers for insuring simultaneous sliding thereof, gearing connecting the rollers of each pair for causing simultaneous rotation thereof, and a pair of belts engaged with the inner and outer rollers respectively, said belts being provided with window cleaning members.

In testimony whereof I have hereunto affixed my signature.

JOHN MONCRIEFF.
